UNITED STATES PATENT OFFICE.

HARRISON D. STERRICK, OF PITTSBURGH, PENNSYLVANIA.

SHAVING AND MASSAGE BRUSH.

Application filed August 7, 1920. Serial No. 401,974.

To all whom it may concern:

Be it known that I, HARRISON D. STERRICK, a resident of Pittsburgh, in the county of Allegheny and State of Pennsylvania, ⁵ have invented a new and useful Improvement in Shaving and Massage Brushes, of which the following is a specification.

This invention relates to shaving and massage brushes, and more particularly to ¹⁰ telescoping shaving brushes having a massage device surrounding the brush.

One object of the invention is to provide in a unitary structure of the class referred to, a reservoir for holding soap, and means ¹⁵ to supply soap to a brush without the necessity of touching it.

Another object is to provide means in a telescoping shaving brush to prevent the turning back of fine bristles as the brush is ²⁰ moved out of the handle.

Referring to the drawings, Fig. 1 is an elevation of a telescoping shaving and massage brush embodying this invention; Fig. 2 is a plan view of the same brush and ²⁵ massage device, the brush being in withdrawn position; Fig. 3 is a central vertical section on the line III—III of Fig. 2; Fig. 4 is a plan view of a soap cartridge for use with the brush of Fig. 1; Fig. 5 is a vertical section on the line V—V of Fig. 4; Fig. 6 is a ³⁰ plan view of a non-telescoping massage brush; and Fig. 7 is a section on the line VII—VII of Fig. 6.

A shaving brush has heretofore been ³⁵ patented, U. S. Patent No. 1,018,939, in which the brush is mounted so as to slide in the handle, as a casing, and a rubber massage device is provided at the forward end of the handle, from which the brush protrudes. As the brush is withdrawn lather in ⁴⁰ it is squeezed out of the massage device, and is in position to be rubbed into the beard of the person shaving. Such a device has many advantages, and has gone into extensive use.

Other brushes have been provided, not of ⁴⁵ the telescoping type however, and not combined with a massage device, in which a soap reservoir was provided, for supplying soap from the reservoir direct to the brush, without touching it with the hands.

The present invention combines all of the ⁵⁰ functions of these prior art brushes, improves them in important respects, and in addition secures new functions, by supply-

ing shaving soap directly to the tip of the brush, where it should be. The prior reservoir brushes of necessity supplied the soap at the interior of the brush, and near its base, ⁶⁰ These have the disadvantage that soap which is left in the brush rapidly destroys the bristles.

The construction of Figs. 1, 2, and 3, embodies a handle, in the form of a tubular casing 1, having a longitudinal slot 2 in ⁶⁵ its side. The bottom of this slot is turned to the left forming a horizontal portion 3, and at the top it is turned to the right forming an upwardly inclined portion 4. A ferrule 5 of a size to slide freely in the interior ⁷⁰ of the casing 1, is provided. The base of this ferrule is closed, but the forward end is open, adapted to receive an ordinary shaving brush 6, mounted in a ring 7, which seats upon interior ribs 8, inside the ferrule. The ⁷⁵ brush is held in firm position by clamping the tip of the ferrule on the ring 7, by cement, or by any other desired means. The bristles of the brush 6 are of such length that when the ferrule 5 is withdrawn to the ⁸⁰ base of the handle, as shown in Fig. 3, the tips of the bristles will be approximately even with the forward end of the casing 1. A pin 9 is fixed in the side of the ferrule 5. The body of this pin extends through the ⁸⁵ slot 2, and the head is positioned just outside of this slot, forming a thumb hold for sliding the brush up and down in the casing as the pin moves in the slot 2.

The forward end of the casing is ⁹⁰ provided with a series of tapered internal ribs or teeth 10. The forward end of the ferrule 5 is tapered, but slightly less than the teeth 10, so that as it advances, and comes into contact with ribs or teeth 10, it tends to form ⁹⁵ a wedged fit.

The ribs 10 and ferrule 5 are so dimensioned that the ferrule comes into contact with the ribs at the forward end of the casing when the pin 4 is in position approximately as shown in Fig. 1. Thereafter a slight pressure to the right on the button 4 tends to turn the ferrule, and at the same time to push it forward until it reaches a wedged fit, and so causes it to be firmly held ¹⁰⁰ in the position shown in Fig. 1. A reverse pressure on the pin releases or unlocks the brush and allows it to slide back to its lower position as shown in Fig. 3.

In telescoping shaving brushes as previ- ¹¹⁰

ously manufactured, it has been found that fine bristles, such as badger hair, used in making up the brush tend to stick to the sides of the casing, and therefore when the brush is moved forward out of the casing these fine hairs turn back around the brush holder, and do not slide clearly out of the forward end of the casing, as they should. This disadvantage has been so pronounced 10 that it has been heretofore impossible to use the softer forms of hair adapted for shaving brush construction in telescoping brushes.

This difficulty has been overcome in the present case by providing a plurality of inwardly extending teeth, or ribs, 10, at the forward end of the casing. These are so positioned apart and extend inwardly to such a distance that they act as a comb for the fine hairs of the brush as it is withdrawn 20 into the casing. They insure that each outer hair of the brush is straightened out and held in proper position when the brush is withdrawn as shown in Fig. 3. Furthermore, when the brush is advanced through 25 the forward end of the casing, these ribs or teeth act as guides, and reinforcers, preventing the fine hairs from turning sidewise, and holding them in small bundles, as it were. This entirely prevents the difficulty above 30 referred to caused by the turning back of fine hairs.

Furthermore, it has been found that in a wedged fit, such as that herein described, a much tighter lock can be obtained by wedging 35 tapered ferrules such as that illustrated, into contact with a plurality of points, such as those formed by the teeth 10, rather than into a solid ring such as would be the case if there were no teeth, but merely the entire 40 forward end of the casing tapered.

This construction requires less metal and results in a lighter handle than where the entire casing is tapered, as has been done heretofore.

45 Furthermore, the locking fit of the brush holder in the teeth is released more readily by backward pressure on the pin 9 where the lock is formed between the tapered brush holder and a plurality of contact points 50 rather than wedging into a solid ring.

Heretofore, rubber massage devices have been mounted on the forward end of the casing of a device such as that just described.

55 The present invention comprises an exterior casing member 12, rigidly mounted by any suitable means, such as welding, or integral casting, at the forward end of the handle 1. This casing 12 is closed at the 60 top except for a small opening 13, made between it and the wall of the handle 1, as shown in Fig. 3. The interior of the casing 12 is threaded, and an annular threaded base member 14 is fitted therein, and adapted to 65 close the rear end of the casing 12, thus

forming an annular chamber 15. Projections 16 are provided on the bottom of the cap 14 providing finger holes for screwing the cap into and out of the casing.

The forward end of the casing 12 is provided with a dovetailed annular projecting portion 17, which holds a rubber member 18, having a cooperating dovetailed recess portion adapted to fit over the portion 17 just referred to, and having a plurality of extensions or fingers 19, forming an annular massage device around the brush 6, as illustrated. The rubber base 18 normally closes the opening 13, but permits soap to be forced out when pressure is applied by cap 14.

The function of the reservoir 15 and screw cap 14, is to hold and supply as needed a plastic shaving soap to the tip of the brush 6. The chamber 15 is filled with the plastic shaving soap, as required, by any desired means. This may be done by removing the cap 14, and filling the reservoir 15 with a shaving soap in paste form, as for example by pressing out the contents of a tube of the ordinary shaving soap into the space 15, and then replacing the cap 14. Or packages or cartridges of shaving soap in paper or tinfoil cartons or containers 20, or otherwise formed may be prepared especially for this device, and may be made to fit accurately 90 into the space 15. These are placed in position so that a projecting neck 21 fits into the hole 13, and the soap will then be squeezed out by pressure of the cap 14, as will be obvious.

Some form of packing member 22 may be provided to fit just inside the cap 14, and to contact with the exterior of the handle 1, to prevent any escape of soap between the handle and cap 14. Preferably this member is made with a spiral incline from one side of 100 hole 13, so that it will squeeze out all the soap, in obvious manner.

In Figs. 6 and 7 a brush to be used for massage alone is shown. The brush 6^a is very short; the rubber fingers 19^a being the same as those already referred to.

In use, the operation of the device is as follows: The reservoir 15 being filled with soap paste, the brush 6 is wet with warm water, and then withdrawn to the position 115 shown in Fig. 3. A partial turn of the cap 16 squeezes out enough soap on the tip of the brush for shaving. The brush is then moved forward, and locked in position 120 shown in Fig. 1, in the manner above described. It is then used as any ordinary shaving brush to work up the soap into a suitable lather for shaving. After this has been done the brush is again withdrawn to the position shown in Fig. 3. This squeezes 125 out a large portion of the lather contained in the brush upon the tips of the fingers 19 and this is then rubbed thoroughly into the face with the rubber massage device. Thereafter the brush is again protruded, and used 130

to again work up the lather for shaving. The whole device may then be dipped into water and the brush will be washed thoroughly clean from lather and soap.

5 I claim:

1. The combination with a shaving brush adapted to telescope into its handle, of a reservoir positioned around the forward end of the handle, and means to force shaving 10 soap from the reservoir upon the tip of the brush.

2. The combination of a tubular handle, a shaving brush slidably mounted therein, a reservoir mounted on the outside of the 15 handle, and means to force soap from the reservoir upon the tip of the shaving brush when it is in withdrawn position.

3. The combination of a tubular handle, a shaving brush slidably mounted therein, a 20 massage device situated around the forward end of the handle, a soap reservoir mounted on the outside of the handle, and means to force soap from the reservoir upon the tip of the brush when it is in withdrawn position.

25 4. The combination of a brush, a rubber massage device around the brush, a soap reservoir around the brush and furnishing a seat for the massage device, and means to force soap from the reservoir onto the brush.

5. In combination, a shaving brush, a casing forming a handle for said brush, the brush being adapted to telescope into the handle, a soap reservoir surrounding the 35 forward end of said handle, a soap-containing carton adapted to fit said reservoir, and means to force soap from said carton upon the tip of the brush.

6. In a collapsible shaving brush, the combination of a hollow handle open at its forward end and having a substantially cylindrical interior, and a brush-holding ferrule slidably positioned inside the handle, the handle having a longitudinal slot through- 40 out a part of its length, the ferrule having a pin fixed therein and extending through the said slot whereby to reciprocate the ferrule inside the handle, the forward end of the handle being restricted on its interior by 45 inwardly extending radial projections

adapted to limit the forward travel of the ferrule in the handle.

7. The combination of a tubular handle, an exteriorly tapered shaving-brush holder slidably mounted in the handle, rigid internal tapered teeth at the forward end of the handle, and means to force the brush holder into wedged engagement with said teeth. 55

8. A shaving brush comprising a tubular handle open at the forward end, a brush holder slidably mounted in the handle, the exterior of said brush holder being tapered towards its forward end, and a plurality of teeth positioned inside the forward end of the handle to cooperate with the tapered portion of the brush holder to hold the brush 60 in operative position.

9. A shaving brush comprising a tubular casing, a longitudinal slot in the casing having a laterally inclined portion at its forward end, a plurality of inwardly extending teeth inside the forward end of the casing, a brush holder slidably mounted inside the casing, said brush holder being tapered towards its forward end and adapted to form 70 a wedged fit or tight contact with said teeth, and a pin fixed in the brush holder and extending through said slot.

10. In a collapsible shaving brush, the combination of a tubular handle open at its forward end, a brush-holding ferrule adapted to slide back and forth in the handle, the handle having a slot extending longitudinally through a part of its length, said slot being inclined laterally at its forward end at 80 an angle to the axis of the handle, a projection from the ferrule extending through said slot, the exterior of the ferrule being forwardly tapered, internal radial projections restricting the forward end of the handle 85 and adapted to engage the exterior of the ferrule when the said projection therefrom is positioned in the inclined portion of the slot.

In testimony whereof, I have hereunto set 90 my hand.

HARRISON D. STERRICK.
